(57) **CLAIM**

I claim the ornamental design for a beverage container, as shown and described.

DESCRIPTION

FIG. 1 is a perspective view of the present invention;

FIG. 2 is a side view of the present invention;

FIG. 3 is a top view of the present invention; and,

FIG. 4 is a bottom view of the present invention.

The broken lines in the drawings are included for the purpose of illustration and form no part of the claimed design.
